UNITED STATES PATENT OFFICE.

SAMUEL MARCUS, OF NEW YORK, N. Y.

ARTIFICIAL EYES FOR DOLLS, DISPLAY-FIGURES, AND THE LIKE.

1,286,045.

Specification of Letters Patent.

Patented Nov. 26, 1918.

Application filed March 2, 1917. Serial No. 151,938.

To all whom it may concern:

Be it known that I, SAMUEL MARCUS, a citizen of the United States, and a resident of New York, in the county of New York 5 and State of New York, have invented certain new and useful Improvements in Artificial Eyes for Dolls, Display-Figures, and the like, of which the following is a specification.

10 The invention relates to improvements in the manufacture of eyes for dolls and other purposes, such as display figures, and the purpose of the invention is to provide an eye of novel structure and also novel means for 15 securing a pair of the eyes within the head of a doll or other figure in such manner that the eyes may roll to closed position when the doll is turned from a vertical to a horizontal position and also to roll to open position 20 when the doll is turned from a horizontal to a vertical position. The eyes are formed of hollow shells of celluloid or equivalent material and fastened by plates to a bridge-piece which connects the eyes in a pair and 25 to which the customary weight for effecting the rolling of the eyes is secured. The bridge-piece connecting the eyes has pivotally secured to its ends cheek-pieces adapted to be secured to the inner side surfaces 30 of the head of a doll by means of shellac or other adhesive applied to said sides over said pieces. My purpose is to sell the eyes in pairs to manufacturers of dolls. The eyes being of celluloid or like material, are sub- 35 stantially unbreakable, and in addition they are light in weight and may be easily manufactured and given a desirable finish.

The invention will be fully understood from the detail description hereinafter presented, reference being had to the accompanying drawings, in which:

Figure 1 is a horizontal section through the upper portion of the head of a doll in line with the eyes, this figure showing a 45 portion only of the doll's head and illustrating the eyes of my invention in position therein;

Fig. 2 is a central horizontal section through the pair of eyes and attached parts, 50 Fig. 2 being on a larger scale than Fig. 1;

Fig. 3 is a front elevation of the same showing the eyes in full, and

Fig. 4 is a back view of one of the eyes and illustrates the metallic parts connected 55 with the eye.

In the drawings, 10 designates the shells

constituting the eyes proper and these shells will preferably be formed of celluloid and are substantially hemispherical and bear an imprint indicating the iris of the eye. The 60 shells 10 are hollow and at their inner edges are flanged inwardly, as at 11. Within the shells 10 are placed plates 12 which bear against the flanges 11 of the shells and are secured to the plates, disks or end portions 65 13 of the bridge 14 which connects the eyes to form a pair of eyes suitable for application to a doll. The plates 12 are of disk outline and preferably they are secured to the plates or disks 13 by means of eyelets 70 15 stamped up from the plates 12 and extended through holes in the plates or disks 13 and flanged over against said disks 13, as clearly illustrated in Fig. 2. The eyelets 15 constitute hollow rivets for connecting 75 the plates 12 and disks 13, and any other suitable connecting means, as a solid rivet or a screw, may be substituted for the eyelets 15, if desired. It will readily be seen that the eyelets 15 serve to clamp the plates 80 12 and disks 13 against opposite faces of the flanges 11 of the shells 10, whereby said shells become very firmly and securely connected with the bridge-piece 14.

The disks 13 are formed at their outer 85 ends with forwardly projecting arms 16 from which eyelets or hollow rivets 17 are struck up, and these rivets 17 are utilized for pivotally connecting cheek-pieces or arms 18 with the bridge 14. The eyelets 90 17 pass freely through holes in the forward ends of the cheek-pieces or arms 18 and are flanged over in a manner permitting said eyelets to constitute pivotal connections, so that while the cheek-pieces or arms 18 are 95 stationary when in the doll's head, the eyes 10 may have the customary rolling motion.

To the bridge-piece 14 is secured the customary weighted rod 19 which tends to hold the eyes horizontal when the doll is sitting 100 or standing or being held in vertical position and causes said eyes to roll to what is called closed position when the doll is reclined or placed horizontally. The rolling of the eyes by the action of the weighted rod 19 is permitted due to the pivotal connection of the eyes with the arms or cheek pieces 18.

In securing the pair of eyes in the head 20 of a doll, the eyes are applied to the position illustrated in Fig. 1 and the arms or cheek-pieces 18 are rigidly fastened at their

- outer or rear end portions against the inner side surfaces of said head by means of shellac, cement or any like substance applied over the same or by other means.
- 5 The advantages of the invention will be apparent without detailed explanation. The structure is one of simplicity, rigidity and durability and may be easily handled and applied to the head of a doll or the like. The eyes or shells 10 are recited hereinbefore as being formed of "celluloid," which is one of the commercial names for pyroxylin material, and in my use of the word celluloid I do not mean to confine this
- 10 invention to the commercial article of material sold under the name "celluloid" as distinguished from other pyroxylin materials of the character of celluloid sold under other trade names.
- 15 What I claim as my invention and desire to secure by Letters Patent, is:
- 20 1. An eye for dolls and the like comprising a hemispherical shell having at its inner edge an inwardly turned flange, a plate within the shell against said flange, a plate exterior to the shell and engaging said flange and means connecting said plates and binding them against said flange.
- 25 2. An eye for dolls and the like comprising a hemispherical shell of celluloid bearing the imprint of the iris and having at its inner edge an inwardly turned flange, a plate within the shell against said flange,

a plate exterior to the shell and engaging said flange, and means connecting said plates and binding them against said flange. 35

3. An eye for dolls and the like comprising a hemispherical shell having at its inner edge an inwardly turned flange, a plate within the shell against said flange, a plate exterior to the shell and engaging said flange, and means connecting said plates and binding them against said flange, said means comprising eyelets struck up from the inner plates and extending through openings in the outer plates and being upset against said latter plates. 40

4. A pair of eyes for dolls and the like, a bridge-piece connecting said eyes and extending beyond the outer edges of the pair of eyes and thereat being formed into arms, and cheek-pieces pivotally secured to said arms and adapted to be rigidly secured within the head of the doll, the means connecting said arms with said cheek-pieces being eyelets or hollow rivets struck up from said arms and extending through said cheek-pieces and upset at their outer ends against the same. 45

Signed at New York, in the county of 60
New York and State of New York, this 28th
day of February, A. D. 1917.

SAMUEL MARCUS.
